UNITED STATES PATENT OFFICE.

FRIEDRICH ALROTH, OF PLAUEN-DRESDEN, GERMANY.

SELF-MOVING CRADLE.

No. 814,420.

Specification of Letters Patent.

Patented March 6, 1906.

Application filed August 5, 1905. Serial No. 272,898.

To all whom it may concern:

Be it known that I, FRIEDRICH ALROTH, a citizen of the Empire of Germany, residing in Plauen-Dresden, in the Empire of Germany, have invented certain new and useful Improvements in Self-Moving Cradles, of which the following is a specification.

The cradles at present in use, in which a rocking movement is imparted to the cradle-body, are in the opinion of medical authorities injurious to the health of the child, having a particularly detrimental effect upon the brain. The well-known "baby-baskets" also have the defect that when the infant needs to be quieted it has to be removed, it being impossible to produce a movement of the basket which will soothe the child.

The object of the present invention is to obviate the above-named defects and to provide a self-moving cradle in which a horizontally-reciprocating movement in either a longitudinal or transverse direction is imparted to the cradle-body.

A further object of the invention is to provide simple and efficient mechanism for automatically actuating the cradle-body.

The novel features of the invention will hereinafter appear and finally be pointed out in the claims.

In the accompanying drawings, in which corresponding parts are designated by the same reference characters throughout, Figure 1 is an end elevation of the improved cradle, the casing for the actuating mechanism being shown in vertical transverse section and the cradle-body being positioned in such a manner as to be reciprocated transversely. Fig. 2 is a top plan view of the motion-transmitting mechanism, the cradle-body and the cover of the casing being removed; and Fig. 3 is a detail view of a portion of said transmitting mechanism.

Referring to the drawings, D indicates the casing in which the actuating mechanism of the improved cradle is housed and upon the top or cover of which the cradle-body m reciprocates. The casing D is composed of two parts, as shown in Fig. 1—a lower part d^x, in which a suitable motor A (illustrated as a spring-motor) is contained, and an upper part d', which houses the motion-transmitting mechanism and to which legs or other suitable supports for the casing D are attached, as shown.

The motor A embodies an upright shaft a, which rotates in step-and-neck bearing in the

bottom of the part or box d^x and extends upwardly into the part d', where it has keyed thereto in any suitable manner a crank b, at the end of which an upwardly-disposed wrist-pin c is arranged. Said wrist-pin engages a horizontally-disposed slotted bar d, which is fixed to a shaft e, extending transversely of the box d' and axially slideable in bearings f therein, said box being provided at either side with apertures through which said rod may extend when at either end of its reciprocating movement, which is effected by the rotation of the wrist-pin c, as will be readily understood. In the embodiment illustrated the shaft e is journaled adjacent one end of the casing d'.

Pivoted at one end, as shown at B, to a pin at the end of the casing d' adjacent the shaft d is a lever i, which extends inwardly through a slot t in said casing, as shown in Fig. 2, and is provided intermediately with a slot y, engaging an upright pin h, extending between the upper and lower side faces of a boxing g, carried by the shaft e, adjacent the slotted bar d. The lever i is also provided with a slot z at its inner end, which engages an upright pin k', extending between two spaced superposed parallel plates k, which constitute a coupling, from which upright rods Z extend upwardly, as shown in Fig. 1. At the upper ends of the rods l, which operate in transverse slots x in the cover of the part d', are placed cross-pieces u, provided with terminal rollers n, movable over said top or cover. The uprights Z and cross-pieces n constitute a carriage upon which is supported in any suitable manner the body m of the cradle.

A handle o serves to wind up the motor A and a hand-wheel p to stop the same when desired.

The operation of the improved cradle is as follows: The motor having been wound by means of the handle o and the wheel p released the motor is started, transmitting rotary motion to the crank b in the direction indicated in Fig. 3. Reciprocating motion is then transmitted to the slideable shaft e, which passes at either end of its movement through the apertures in the part d'. The reciprocating motion of said shaft thus serves to rock the lever i upon its pivot B through the medium of the pin h co-operating with the slot y, and the inner end of the lever i therefore describes a comparatively long arcuate movement, carrying with it the coupling member k and the carriage constit-

tuted by the cross-pieces *u* and rollers *n*. As the body *m* is secured to said carriage a horizontal reciprocating movement is thus imparted to the same. As shown, the body *m* is adapted to be reciprocated transversely; but it is obvious that by shifting the same on its carriage it may be reciprocated longitudinally.

Having thus described my invention, I claim as new and desire to secure by Letters Patent—

1. In a self-moving cradle, a casing, a lever pivoted adjacent one end of said casing and extending into the same, mechanism in said casing for rocking said lever, a carriage attached to the inner end of said lever, and a cradle-body mounted on said carriage and movable over the top or cover of said casing.

2. In a self-moving cradle, in combination, a casing, an axially-slidable shaft therein, a slotted bar carried by said shaft, a crank having a wrist-pin engaging the slot in said bar, means for rotating said crank, a cradle-body above said casing, and an operative connection between said shaft and said body.

3. In a self-moving cradle, in combination, a slidably-mounted shaft, means for reciprocating the same, a lever rocked by said shaft, and a reciprocating cradle-body attached to one end of said lever.

4. In a self-moving cradle, in combination, an axially-slidable shaft, means for reciprocating the same, a pivoted lever operable by said shaft, a carriage attached to the free end of said lever, means for guiding said carriage, and a cradle-body mounted on said carriage.

5. In a self-moving cradle, in combination, an axially-slidable shaft provided with a pin, a lever pivoted adjacent said shaft and having a slot engaging said pin, a cradle-body attached to the free end of said lever, and means for supporting and guiding said body.

6. In a self-moving cradle, in combination, a casing, a transversely-disposed axially-slidable shaft mounted in said casing adjacent one end thereof, means for reciprocating said shaft, a lever pivoted adjacent the end of said casing and rockable by said shaft, a carriage carried at the free end of said lever and embodying rollers movable on the top or cover of said casing, and a cradle-body mounted on said carriage.

In testimony that I claim the foregoing as my invention I have signed my name in presence of two subscribing witnesses.

FRIEDRICH ALROTH.
